Patented Feb. 3, 1976

238,689

COMBINED AQUARIUM AND MIRROR

Samuel Shalom, 577 Grand St.,
New York, N.Y. 10002

Filed Jan. 21, 1974, Ser. No. 435,003

Term of patent 14 years

Int. Cl. D30—02

U.S. Cl. D30—11

FIG. 1

FIG. 2

FIG. 3

FIG. 4

FIG. 1 is a perspective view of a combined aquarium and mirror, showing my new design;

FIG. 2 is a rear elevational view thereof;

FIG. 3 is a left side elevational view; and

FIG. 4 is a cross-sectional view along line 4-4 of FIG. 2.

I claim:

The ornamental design for a combined aquarium and mirror, substantially as shown and described.
